UNITED STATES PATENT OFFICE.

HARVEY BOSWORTH, OF PLATTSBURG, NEW YORK.

DESIGN FOR A FRUIT AND VEGETABLE KNIFE.

46,161.

Specification for Design.

Patented July 28, 1914.

Application filed June 16, 1914. Serial No. 845,493. Term of patent 14 years.

To all whom it may concern:

Be it known that I, HARVEY BOSWORTH, a citizen of the United States, residing at Plattsburg, in the county of Clinton and State of New York, have invented a new, original, and ornamental Design for Fruit and Vegetable Knives, of which the following is a specification, reference being had to the accompanying drawing, forming part thereof.

I claim:

The ornamental design for a fruit and vegetable knife, as shown.

HARVEY BOSWORTH.

Witnesses:
